DESIGN FOR A DRESS ENSEMBLE

Elizabeth M. Ciccone, New York, N. Y.

Application December 15, 1937, Serial No. 73,629

Term of patent 3½ years

To all whom it may concern:

Be it known that I, Elizabeth M. Ciccone, a citizen of the United States of America, residing in city of New York, county of New York, and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view of the jacket portion.

Fig. 3 is a front view of the dress member of the ensemble.

Fig. 4 is a rear view of Fig. 3.

My design is characterized by the specific raised stitching on the jacket portion of the ensemble in combination with the raised stitching on the sleeves and bottom waist portion of the dress as shown.

I claim:

The ornamental design for a dress ensemble substantially as shown and described.

ELIZABETH M. CICCONE.
